UNITED STATES PATENT OFFICE.

FREDERICK W. LEONHARD, OF BUFFALO, NEW YORK.

DOOR FOR FLOORS AND SIDEWALKS.

1,115,554.

Specification of Letters Patent.

Patented Nov. 3, 1914.

Application filed July 17, 1913. Serial No. 779,501.

To all whom it may concern:

Be it known that I, FREDERICK W. LEONHARD, a citizen of the United States, residing at Buffalo, in the county of Erie and State of New York, have invented new and useful Improvements in Doors for Floors and Sidewalks, of which the following is a specification.

This invention relates to a trap door for sidewalks, floors or similar purposes.

The objects of this invention are to provide a door having a walking surface of concrete which is not as slippery as and is more durable than steel or iron, to provide a concrete slab which is of shallow depth and great strength so that the same may be counterbalanced by a minimum weight, to provide means for counterbalancing the door at all points of the vertical arc through which it swings so that it may be opened or closed with a minimum amount of effort, to provide means for pivotally supporting the door on the underside of the walk or floor so as to keep the pivotal connections free from dirt, snow or ice and have them easily accessible for inspection, oiling or repairing and carry dead load only, to provide a door with a walking surface that is absolutely flush with the walk or floor when the door is closed, to provide means whereby the door is waterproofed at side, heel and toe, to provide the door with means whereby the same is locked automatically both in its closed and in its open positions and may be released conveniently, and to so organize the parts that when the door is closed no part of it seriously interferes with the underhead room and when the same is open no part of it interferes with the well opening so that the same is freely accessible from above and below, to provide a door which is practically indestructible, to provide a door having glass vault lights in a reinforced concrete slab and to provide a door which permits the glass vault lights to be placed directly on and locked to the tensile reinforcement of the concrete slab.

In the accompanying drawings: Figure 1 is a longitudinal sectional elevation of the door embodying my improvements, the left half of the same being in a closed position and the right half in an open position.

Fig. 2 is a vertical section of the door in its fully open position. Fig. 3 is a plan of the door corresponding to Fig. 1 with the parts of the sidewalk or floor removed. Fig. 4 is a section showing the rear view of the hinge for pivotally connecting the door with the floor, the section being taken in line 4-4, Fig. 5. Fig. 5 is a side elevation of this hinge and adjacent parts. Fig. 6 is a transverse section, on an enlarged scale, of the cross shaped bar which connects the heel and toe bars of the door, the section being taken in line 6-6, Fig. 3. Fig. 7 shows a cross section of the spring joint for one of the guard gate braces the section being taken in line 7-7, Fig. 8. Fig. 8 is a top view of the same. Fig. 9 is a fragmentary plan view, on an enlarged scale, of a door slab showing the frame angles and the details of the vault lights, reinforcement and method of fastening same. Fig. 10 is a vertical section of the same. Fig. 11 is a vertical section showing the method of tying the minor to the major reinforcement. Fig. 12 is a cross section through the side portion of the door, well frame and gutter. Fig. 13 shows a longitudinal section of the door through the toes of the opposing door leaves showing how the trough shaped bar of one leaf empties into one of the side gutters. Fig. 14 shows a fragmentary longitudinal section of the door showing the heel part of one door leaf, well frame and adjacent gutter.

Similar characters of reference indicate corresponding parts throughout the several views.

In its general construction the door, as shown in the drawings, comprises two door leaves A, two longitudinal counterbalanced supporting beams or levers B, B for each leaf connected at their front ends with the underside of said leaf at the side edges of the same, hinges C for pivotally connecting the central parts of said beams with the undersides of the floor, a counter weight D connected with the rear end of each beam, 100 braces E connecting the beams of each door leaf, automatic guard gates F arranged on the beams, heel gutters G for draining the heels of the door leaves, a toe gutter G¹ for draining the joint between the toes of the 105 door leaves, side gutters G² for draining the

sides of the door leaves, and locking dogs H and H¹ for holding the door leaves in their open and closed positions.

It is to be understood that the toe is 5 the transverse edge of the door leaf farthest from the pivot of the same, the heel is the transverse edge of the door leaf nearest to its pivot and its sides are the lateral edges of the door leaf extending from the heel to 10 the toe.

41 represents the floor or sidewalk over the vault which may be constructed in any suitable manner and which contains an opening or well. The edge of this well is 15 preferably bound by a metal frame 6 of L-shaped form in cross section.

Each of the door leaves comprises two longitudinal side bars 1, 1, a transverse heel bar 2 connecting the rear ends of the side 20 bars, a transverse toe bar 4 connecting the front ends of the side bars, a longitudinal central bar 5 connected at its front and rear ends with the toe and heel bar, reinforcing wires 9, 10 connecting the bars, bolts 11 and 25 12 for connecting the reinforcing wires with the bars, a slab 13 of concrete which is supported on the bars and in which said reinforcements are embedded, transparent vault lights 14 of glass or similar material, and 30 metal sockets or receptacles 15 for said vault lights mounted on said reinforcement. The frame bars 1, 2, 4 and 5 may be standard rolled angles or may be special rolled shapes. The bars 1, 2 and 4 form the four sides of 35 a square or rectangular frame and the vertical legs or flanges of the same provide protection for the edges of the concrete slab 13 while the horizontal legs or flanges thereof provide a seat for the concrete slab 13, 40 also a place for attachment of the reinforcement 9. The central bar 5 is cross shaped in cross section and extends longitudinally on the center line of the door and connects the heel and toe bars 2, 4. The slab 13 is 45 additionally supported by the reinforcement 9 and the latter is attached to the longitudinal bar 5 thus dividing the rectangular frame into approximately two squares, each of which contains a section of the slab.

50 Each of the side bars 1 is preferably Z shaped in cross section, as shown in Fig. 12, and has an upper flange 1^a overlapping the upper edge of the well frame 6, a lower horizontal flange 1^b which forms a seat for the 55 concrete slab 13 and to which the reinforcement 9 is tied, a vertical web 1^c connecting these two flanges and forming a protection for the edge of the slab 13 and a depending drip bead 1^d which is formed on the under- 60 side of the lower horizontal flange at its junction with the vertical web. This drip bead is adapted to shed all water which finds its way beneath the upper horizontal flange into the longitudinal gutter G² ar- 65 ranged on the inner side of the longitudinal

member of the well frame, as shown in Fig. 12. The heel cross bar is also of Z shape form in cross section and has a lower horizontal flange 2^a and depending drip bead 2^b which directs any water finding its way 70 beneath the horizontal flange 2^c into the transverse gutter G arranged on the adjacent part of the well frame. The upper horizontal flange 2^c of the heel bar is also similar to that of the side bars and in addition it has a slight extension 2^d toward the toe of the door which eliminates the feather edge of the concrete slab 13 and also locks the same securely along the heel. The connecting web 2^e between the flanges 2^a, 2^c, is 80 oblique instead of vertical and bent at such an angle that the upper end forms practically a tight joint with the well frame 6 when door is closed and gives a considerable clearance for the lower end and drip bead 2^b 85 when the door is closing thus eliminating the possibility of the bead fouling the well frame, as shown by dotted line 2^f which is a portion of an arc whose radius is the distance from the center of the hinge to the 90 upper inside edge of well frame. The upper sides of the slab and door frame are flush and the upper edge of the well frame stops short of the top of the floor so that the door is flush with the floor, as shown in 95 Figs. 12 and 14.

In a double door *i. e.* a door of two leaves A, such as that shown in Figs. 1, 3 and 13, it is necessary to take care of the water coming in along the toe joint between the two leaves. In this case each of the toe cross bars has an upright web 4^a engaging the edge of its companion slab 13 and a horizontal flange 4^b at the lower edge of the web which supports this slab. At its upper edge the web of one toe cross bar is provided with a laterally projecting flange 4^c which engages with a rabbet 4^d in the upper edge of the toe cross bar of the other leaf, thereby forming a joint between the same and 110 also causing the leaf with the flange 4^c to operate as a lock for the leaf having the rabbet 4^d. At the junction of the vertical web and lower horizontal flange of the toe cross bar having the flange 4^c is arranged a 115 depending drip bead 4^e which directs any water passing through the toe joint into the trough or gutter G¹ arranged at the lower edge of the toe bar of the other leaf. The opposite ends of the toe bar gutter G¹ project over into the gutters G² of the side bars of the well frame so that the water from the toe gutter enters the same. The heel gutters G and the side gutters G² connect with each other at the corners of the well and any 120 water entering the same is carried away by a drain pipe 38 connecting with the heel gutter, as shown in Figs. 3 and 14.

The central bar 5 is cross shaped in cross section and may either be rolled in one piece, 130

as shown in Fig. 6, or built up in any suitable manner. The horizontal flanges 5^a of the central bar form a seat for the concrete slab 13 and a place for attaching the reinforcement. These various bars are riveted or bolted together at their various junctions by flat connection plates or gussets 8 and when the door is closed they rest on the edges of the gutters thus eliminating the possibility of any live load acting on the hinges C.

The reinforcement for the door slab 13 shown, in Figs. 3, 9, 10 and 11, is composed of steel wire of high tensile strength and is divided into two parts *i. e.* the major 9 and the minor 10 reinforcements. The major reinforcement 9 is made by weaving the wires at right angles to each other. Along two sides of the slab 13 these wires have loops 9^a at one end which engage the head 9^b of a specially designed bolt 11 by means of which they are tied to the door frame bars. On the other two sides of the concrete slab the opposite ends of the wires 9 are stretched around and securely fastened to the adjacent frame bars by other specially designed bolts 12 by means of which any slack in these wires may be taken out and certain initial stress given to the same. The advantage of this tying and stretching is five fold. First, it gives a taut rigid mesh in which each wire is doing its full share of work, thus making the slab 13 capable of standing a load at least 10 to 12 times that of a slab reinforced in the ordinary manner or of a slab whose reinforcement is tied but not stretched. Second, the reinforcement is so rigid that it practically takes all the load and whatever beam action there may be, the steel acts immediately instead of allowing an initial deflection to take place in the slab necessary to stretch the slack out of the reinforcement as is the case in ordinary reinforced concrete work. This prevents the concrete from being stretched beyond its elastic limit and cracking of same. Third, it thus becomes only necessary to make the slab 13 of a minimum thickness to afford a good walking surface and provide the necessary stiffness. Fourth, it permits placing the metal cups 15 incasing the glass vault lights 14 directly on the tensile reinforcement and locking them thereto. Fifth, in a reinforced concrete slab of small depth and small span it is hard to develop strength of reinforcement by bond to concrete. Tying and stretching eliminates this difficulty.

The minor reinforcement, see Figs. 9, 10 and 11, consists of steel wires placed adjacent to the vault lights 14 in each alternate rectangular mesh formed by the major reinforcement. They are of such length as will string diagonally across one mesh, wrap once around the junction of the major reinforcement and allow the free end 10^a to

stick up vertically into the concrete. The object of this reinforcement is to give a local support for the concrete and to anchor the concrete securely to the major reinforcement.

The special bolt connections, see Figs. 9 and 10, are two in number, the first being a tie bolt and the second a winch bolt. The tie bolt is similar to an ordinary bolt except that the head 9^b is elongated in the direction of the major reinforcing wire which it engages and is provided at the outer end of the elongation with a depending hook or lug 9^c which receives the loop 9^a on the wire 9 of the major reinforcement. The advantage of this bolt is that it provides a quick and secure tie and keeps the reinforcement at a certain definite distance from the bottom of the slab 13. The winch bolt 12 is also similar to an ordinary bolt with a hexagon head except that a vertical groove 12^a is cut in one of its six sides. This groove is of such depth that the upturned part 12^b of the wire 9 which is seated in this groove projects a little beyond the face or side of the bolt head. The object of this groove is best shown by the following explanation as to the method of fastening wire. The bolt 12 is placed in the punched hole of the lower horizontal flange of the respective frame bar with the head on the upper side and the nut 12^c put on but not tightened. The wire of the major reinforcement is placed between the underside of the bolt head and the upper side of the lower horizontal flange of the frame bar and on the side of the bolt shank so that the pull of the wire around the shank of the bolt would tend to tighten the same. The wire is then pulled as tight as possible by hand and given a one eighth turn around the shank and then bent up into the groove in the bolt head. The wrench is now applied with one jaw gripping the side of the bolt head which contains the groove. This holds the wire securely and the bolt is turned until the wire is tightened the desired amount and then the nut is turned tight. The advantage of this is that it provides for the major reinforcement a quick and secure attachment, taking out all slack and giving a certain initial stress. As the shank of the bolt turns with the wire it thus prevents any local or concentrated stretch of the wire and possible injury therefrom.

The slab provides a wearing or walking surface and may be of cement or bituminous concrete or other suitable material. The concrete locks the metal receptacles for the vault lights laterally in place.

The glass vault lights 14 are circular in plan and threaded on the circumference, as shown at 14^a, so as to screw into the metal receptacle. They are flat on the top and spherical on the bottom except a small flat

shoulder 14^b around the bottom edge which forms a seat for the gasket 16. The extreme edge 14^c of this shoulder is slightly acute so as to grip the gasket.

- 5 The exterior of the metal receptacles is circular in plan at the upper surface and has an upper octagonal form 14^e in the plane of the reinforcement and a lower octagonal form 14^d at the lower surface.
- 10 These two octagons are not of the same size in plan and are not equilateral but are formed of four alternate long and short sides. The four long sides of the lower octagon 14^d produced would form a square 15 slightly less in size than the square mesh formed by the wires of the major reinforcement. The two octagons are separated by a circular groove, channel or canal 15^a which receives the major reinforcement and this 20 canal forms an inscribed circle in the square formed by the long sides of the lower octagon. The advantage of this construction is that by placing the long sides of the lower octagon parallel with the wires of the major 25 reinforcement the cup 15 drops through the mesh until the lower side of the upper octagon bears on the major reinforcement. The cup is then turned horizontally 45 degrees until the wire reinforcement lies in the circular canal. This forms the vertical lock 30 for the cup or receptacle and the surrounding concrete forms the horizontal lock. The inside of the cup is circular in plan and threaded to receive the thread of the glass 35 vault lights. A clearance is provided between the inside of the cup and the vault light which is filled with suitable cement 15^b to provide for expansion. Around the inside lower edge of the cup there is a shoulder 15^c the edge of which is slightly acute so as to grip the gasket. The vault lights 40 rest on the gasket which forms a tight joint and the gasket is held in place by a metal collar 15^d which in turn is fastened to the 45 underside of the metal cup by tap screws 15^e, as shown in Fig. 10.
- Each of the beams B is of irregular shape 50 and is composed of a load arm 18, a weight arm 19, a connection piece 20 between the two arms and a hinge plate 21. The weight arm supports the counterweight D and is composed of a channel or other suitable shape. It lies in a horizontal position when the door is closed and is inclined when the door is open. At its outer end it has a means for the attachment of the counterweight D and at the inner end its back is riveted to the inside of the adjacent hinge plate 21. At one end its back is riveted to 55 the outside of the hinge plate 21 in a downward oblique direction and at such an angle that it becomes horizontal when the door is open. The load arm 18 is composed of an angle or other suitable shape and it supports the door leaf at its outer end. The

inner end of the load arm is bent at its junction with the connecting piece 20 and is riveted to the back of the lower end of this connection piece 20, this riveting being further strengthened by a clip angle 22 which is also riveted to the back of the connection piece 20 and to the horizontal leg of the load arm angle 18. The load arm 18 has a second bend near its outer end where it joins the side bars of the door leaf which point is approximately one half the distance between the heel and toe bars. That portion of the load arm 18 between said outer bend and its outer end is horizontal and parallel to the weight arm when the door is closed. This horizontal leg forms the support for the door slab and it is riveted or bolted to the horizontal leg of the side bars of the frame. The arm 18 is straight between the two bends mentioned above and to this straight part are riveted two clip angles 23 for supporting the automatic guard gates. This arm affords a place for connecting the brace angles E. It also forms a support for the brace 25 which gives an auxiliary support to the side bars 1, 1, of the door leaf at a point approximately one half the distance between the heel and the point where the load arm joins the side bars. The load arm besides affording a means of support for the door and automatic guard gates also acts as a transverse guide to bring the door to its proper seat.

The hinge gate 21 is riveted between the backs of the weight arm channel 19 and the connection piece channel 20. It extends above the horizontal flange of the weight arm through which extension is bored a hole to receive the hinge pintle. Through the edge of the hinge plate from the rear is bored a hole 26 to the pin bearing to receive a set screw 27 by which means the pin is set to the hinge plate, thus making the pin revolve in the jaws of the hinge. The hinges C are of the ordinary type with two vertical jaws bored to receive the pin and holes in the horizontal flanges to receive the stay bolts. The hinges take dead load only.

The counterweights may be of concrete or other suitable material hung on a rod or hook which engages a hole in the outer end of the weight arm. As the center of gravity of the automatic guard gates is practically the same distance from the hinge C whether the door is closed or open and as it is desirable to have the moment of the lead arm slightly greater than the moment of the counterweight arm in order to overcome any possible tendency of the door kicking up should the locking device become defective and yet have a door that is practically balanced at all points of the vertical arc through which it swings, the position of the counterweight to take care of these conditions is arrived at as follows:

Assuming that the weight of the load arm 18 and the bracing E balances the weight of the weight arm 19 and further assuming that the center of gravity of the door leaf and guard gates F is at a point half way between the heel and toe and on the underside of the leaf then by fixing the length of the weight arm 19 the position of the counterweight D must be on a line which passes through the hinge pin 26 and the center of gravity of the load *i. e.* door leaf and guard gates, as at X at the left side of Fig. 1. By placing the counterweight slightly inwardly from X toward hinge C as at Y the condition of load moment, being greater than weight moment is fulfilled and placing the weight slightly above Y as at Z it gives the same effect as at Y when door is in the closed position but Z gives a slight increment to the weight moment as the door opens thus taking care of the constant movement exerted by the guard gates F. By figuring the weights and center of gravity of the various parts the exact position may be calculated.

The bracing E comprises a channel 28 which runs between the two connection pieces 20 and is riveted to the top flanges of same by means of gussets, two angles 24 which run from gussets at the outer end of the load arms 18 to a gusset riveted to the lower flange of the brace channel 28 at its center of span.

The automatic guard gates F are hinged to the horizontal legs of the clip angles 23 on the load arm and swing through the same vertical arc with the door. They are composed of flat iron bars riveted in the shape of a Warren truss. The top and bottom cords 30, 31 of the gates on the lock leaf having the locking flange 4° are of such length that these gates swing within a circle whose radius is slightly less than the distance from the hinge pin of this leaf to the toe of the opposite trough leaf having the trough G¹ so as to give a slight clearance therebetween. The gates of the trough leaf are of such length so as to swing and give a slight clearance on the gates of the lock leaf. This permits the lock leaf to be fully opened by disconnecting a chain f between the two opposite gates without disturbing the trough leaf. It also permits the two door leaves to be closed at the same time without interference from the gates.

At the junction of the top cord 30 and the outer web member 32 of each gate the connection with the chains f is made by means of a tie bolt similar to that used for tying the reinforcement. To the nose of this tie bolt the chain f is attached which thus gives a flexible connection between the gates of the opposite leaves both when the door is closed or open or any intermediate position. Each of these gates is held lat-

erally by an iron brace preferably composed of two bar sections 33, 33^a having their extremities hinged to the top cord 30 and to the clip angles 23^a riveted to the underside of the central bar 5 of the respective door leaf. The opposing ends of the brace sections are connected by a flexible spring joint so that the gate may be folded flat on the leaf when the door is open after disconnecting chain f thus giving access to the well 75 opening. This spring joint preferably comprises a pivot pin or rivet 34 connecting the opposing ends of the brace sections 33, 33^a and a spring finger 34^a being an extension of the brace section 33 toward the brace section 33^a and provided with an abrupt stop 34^b and a rivet head or wedge projection 34^c adapted to engage with opposite sides of the brace section 33^a, while this brace is straightened. For folding this brace its members are turned in a direction for moving the stop 34^b away from the section 33^a and carrying the wedge projection 34^c underneath the same. The advantage of this is that in breaking the joint the upper bar 90 passes over the lower bar and rivet head 34^c which tends to spring that portion of the lower bar forming the finger, thus offering the necessary resistance to keep the joint rigid for all axial forces but the joint may 95 be easily broken by a lateral force intelligently applied by the hand on the same side of the brace member on which the rivet head 34^c is arranged. In other words the joint is held rigid on one side from axial 100 forces by a couple of which the rivet connection is one force and the comparatively flat projection 34^c in conjunction with the spring resistance of the finger portion of the lower bar forms the second force. If 105 before the door is closed it is neglected to unfold the gates F they will fall by gravity into that position when the door is closed and thus be ready to protect the well when the door is reopened. When the gates are 110 closed the two bars forming each brace are slightly longer than a dead center line drawn between the two hinges at the opposite ends of the brace thus allowing the flexible joint to go slightly beyond or be slightly eccentric with this line. This eccentricity brings the spring joint members above mentioned into play and any force which tends to open the gates inward tends to increase this eccentricity thus holding 115 the joint rigid.

By extending the horizontal leg of the clip angles 23 which attach the top and bottom cords 30, 31 of the gates to the load arms, so that their hinges are beyond the vertical leg of the load arm angle the gates F when door is open may be swung outward over the sidewalk as well as inward over the well by simply detaching either end of the gate braces.

If desired only one door leaf and associated parts need be employed in the case of a well of comparatively small area.

Locking means are provided for holding the door leaves in both closed and open positions, these means preferably comprising the two pairs of locking dogs H, H¹. The first set of dogs H lock the door in the open position and the second H¹ lock the same in its closed position. The members of the first set of locking dogs are situated on the outside of the counterbalanced beam and are fastened to the underside of the walk or floor and automatically engage a lug angle h riveted on the outside of the connection piece 20 and can be released from above by a rope h¹. The members H¹ of the second set of locking dogs are situated on the inside of the counterbalanced beam and are also fastened to the underside of the walk or floor so as to engage the upper flange of the weight arm, as shown in Fig. 1. The last mentioned dogs may also be released by a rope conveniently placed similar to that used in connection with the dogs H or by any other suitable means.

I claim as my invention:

1. The combination of a floor having a well, a door adapted to close said well, a two armed lever pivoted to swing vertically on the underside of said floor adjacent to one edge of the well and having its front arm connected with the underside of said door between the heel and toe thereof said lever having its front arm deflected downwardly adjacent to the fulcrum thereof while its rear arm is arranged underneath said floor, and a counterweight mounted on the rear arm of said lever.
2. The combination of a floor having a well, a door adapted to close said well, a two armed lever pivoted to swing vertically on the underside of said floor adjacent to one edge of the well and having its front arm connected with the underside of said door between the heel and toe thereof said lever having its front arm deflected downwardly adjacent to the fulcrum thereof while its rear arm is arranged underneath said floor, a counterweight mounted on the rear arm of said lever, and means for locking said lever in an open and in a closed position.
3. The combination of a floor having a

well, a door adapted to close said well, a beam or lever pivoted on said floor and carrying said door, and means for locking said door in its closed and in its open positions comprising dogs pivoted on the underside of said floor and adapted to engage with said beam or lever on opposite sides of its axis.

4. The combination of a floor having a well, a door adapted to close said well, a beam or lever pivoted on said floor and carrying said door, and means for locking said door in its closed and in its open positions comprising dogs pivoted on the underside of said floor and adapted to engage with said beam or lever on opposite sides of its axis and releasing lines connecting with said dogs.

5. The combination of a floor having a well, a door adapted to close said well, two levers pivoted to swing vertically on the underside of the floor adjacent to opposite corners of the well and each having a front arm which is connected with the underside of said door between the heel and toe thereof and is deflected downwardly adjacent to its fulcrum to form an elbow and also having a rear arm arranged underneath the floor, a counterweight connected with the rear arms of said levers, and a transverse beam connecting the elbows of both levers.

6. The combination of a floor having a well, a door adapted to close said well, two levers pivoted to swing vertically on the underside of the floor adjacent to opposite corners of the well and each having a front arm which is connected with the underside of said door between the heel and toe thereof and is deflected downwardly adjacent to its fulcrum to form an elbow and also having a rear arm arranged underneath the floor, a counterweight connected with the rear arms of said levers, a transverse beam connecting the elbows of both levers and oblique braces connecting the central part of said beam with the front parts of the front arms of both of said levers.

Witness my hand this 16th day of July, 1913.
